UNITED STATES PATENT OFFICE.

CHARLES F. RABENOLD, OF PHILADELPHIA, PENNSYLVANIA.

DESIGN FOR A LAMP CASING.

Application filed January 4, 1921. Serial No. 435,031. Term of patent 7 years.

To all whom it may concern:

Be it known that I, CHARLES F. RABENOLD, a citizen of the United States, residing at Philadelphia, in the county of Philadelphia and State of Pennsylvania, have invented a new, original, and ornamental Design for a Lamp Casing, of which the following is a specification, reference being had to the accompanying drawing, forming a part thereof, in which—

Figure 1 is a perspective view of the front

of a lamp casing showing my new design, and

Figure 2 is a rear perspective view of Figure 1.

I claim:

The ornamental design for a lamp casing, as shown.

CHARLES F. RABENOLD.
